WINDOW SEAT AND PLATFORM

Frank A. G. Denst, Chicago, Ill.

Application April 21, 1944, Serial No. 532,038

3 Claims. (Cl. 304—24)

This invention relates to improvements in window seats or scaffolds.

The main objects of this invention are to provide a novel and improved window seat or scaffold; to provide such a device which is adjustably mountable and adaptable to substantially all types of window sills and window ledges; to provide a device of this character which is constructed entirely of wood with the exception of the hook bar; to provide a device of this character having an adjustable means for locking the seat or scaffold to the window sill and ledge, whereby said seat or scaffold is securely anchored thereto; and to provide a device of this character which is simple in construction, safe and convenient to use, readily adjustable for application to window sills of various widths and offsets, and relatively inexpensive to manufacture.

A specific embodiment of this invention is shown in the accompanying drawing in which:

Figure 1 is a perspective view of my device.

Fig. 2 is a vertical cross sectional view of the same taken on the line 2—2 of Fig. 3, as applied to a window which is also shown in section.

Fig. 3 is a front elevational view of my device, the hook bar being shown in cross section.

Referring in detail to the drawing, my improved window seat or scaffold is preferably constructed entirely of wood and comprises a seat member 1, a pair of side frame members 2 and 3 having portions cut out therefrom as indicated by the numerals 4 and 5, a centrally disposed partition or supporting frame member 6 located medially of the seat 1 and extending between the side walls 2 and 3, and a hook bar 7, preferably constructed from band iron, having a plurality of apertures 8 contained therein.

The hook bar 7 is located below the seat 1 and slidably anchored to the lower face thereof by staples 9 and 10 which also act as guides to keep the hook bar 7 in alignment whereby the same will extend centrally from the seat structure in a plane transverse to the long plane of the seat 1. The hook bar also extends through a slotted aperture 11, formed by cutting a notch in the upper edge of the partition member 6.

The hook bar 7 is bent at right-angles to the plane of the bar at its extreme outer end and then rearwardly and forwardly to form a hook 12 which is adapted to extend over the window sill 13 for clamping engagement with the sill board 14 when the device is in use.

It is to be noted that the hook bar 7 is offset as at 15 whereby portion 16 is adapted to lie

flat against the sill board 14 to insure a proper clamping action between the hook 12 and the sill board 14. This offset 15 also performs the function of preventing the main portion of the bar 7 from mutilating or destroying any weather striping, etc., 13' applied to the window sill 13.

The cutaway portions 4 and 5 contained in the two end members 2 and 3 respectively are identical in shape.

10 Since the upper surfaces of substantially all stone window ledges are sloped downwardly, whereby to assure proper and thorough drainage of any water, etc. therefrom, it is to be noted that the upper edges 17 and 18 respectively lie 15 in an angular plane which substantially conforms to the slope of the stone ledge 19, (or as shown in Fig. 2 it may be slightly greater) whereby these edges 17 and 18 will seat thereon.

The front edges 22 and 23 of the legs 20 and 21 respectively of the side frame members 2 and 3 respectively are adapted to bear against the face 24 of the building. These legs 20 and 21 are also arranged to lie below the lower edge of the stone ledge 19.

25 It will now be apparent from the foregoing description that the side frame members will embracingly engage the stone window ledge 19 (see Fig. 2).

Since the distances between the outer face edge 30 of the stone ledge and the inner face edges of the sill board vary with the various types of buildings, I found it desirable to be able to vary the length of the hook bar 7 at will in order that my window seat may be used almost universally 35 on substantially all types of windows. I accomplish this by providing a series of apertures 8 in the hook bar 7 whereby when the device of my invention is seated on the stone ledge and hook 12 is in position on the sill board, the cotter pin 25 is inserted through the aperture 26 contained in the seat 1 and through one of the apertures 8 in the hook arm 7 which will be found to be in alignment with the aperture 26.

40 When the legs of the cotter pin are spread apart, 45 the hook arm 7 will be semi-permanently secured to the seat 1.

Since all windows in a given building are usually all substantially alike, one adjustment of the hook arm to fit the conditions of one window in 50 the building is usually sufficient whereby the device will fit all of the windows in the building. If the device is to be used in a single building only and all the windows are the same, so that the hook never need be readjusted after being 55 adjusted to one of the windows in the building,

the hook arm, if it is so desired, may be permanently anchored to the seat by inserting a wood screw 27 through one of the apertures 8 and into the seat 1. Of course, the length of the screw should be such as to not protrude through the face of the seat 1 as will be understood.

It is also to be understood that the aperture 26 is countersunk whereby the head of the cotter pin will be embedded in the seat proper so as not to protrude above the upper surface of the seat.

The normal tendency of a person sitting on the stone ledge of the window, when washing the windows or doing any work on the window frame, etc., is to hold the body, i. e. the trunk from the hips to the head, in a diagonal plane toward the window. This is because the only firm purchase usually had is obtained by hooking the legs, i. e. from the knees to the feet, over the sill board 14. When using the seat of my invention the user will have the tendency to assume the same position.

Therefore, all the weight of the person using my window seat will be concentrated on the seat per se, and directed toward the front edge thereof. It will, therefore, be apparent that the upper edges 17 and 18 of the cutout portions 4 and 5 of the side frame members 2 and 3 respectively will substantially carry the entire weight exerted on the seat and such weight will be exerted in a vertical plane so that substantially no outward horizontal pressure is exerted on the hook arm 1. Under such conditions mutilation of the window sill board 14 is substantially nil and the usual danger of breakage of the sill board is also eliminated.

It will also be understood that the hook 12 may, if desired, be covered with suitable padding to insure against chipping or scratching of the paint on the sill board.

The device of my invention may be used as a seat or a platform for a person (1) washing windows, or (2) installing or replacing window panes, (3) painting sash, etc., and for many other analogous uses.

Although but one specific embodiment of this invention is herein shown and described, it is to be understood that details thereof may be altered or omitted without departing from the spirit of the invention as defined by the following claims.

5 I claim:

1. In a device of the class described comprising a seat member, a pair of side frame members secured to the lower face of said seat member, 10 a partition member located centrally below and secured to said seat member, said partition member also being positioned between said side members and anchored thereto, a portion of each of said side members being arranged to protrude 15 beyond the inner forward edge of said seat member and having portions cut out therefrom whereby to embracingly engage a stone sill of a window, and means secured to said seat member extending longitudinally therefrom adapted to engage 20 the sill board of a window frame and lock said device to the window frame.
2. The device as set forth in claim 1 wherein said means is adjustable.
3. In a device of the class described comprising 25 a seat member, a pair of side frame members secured to the lower face of said seat member, a partition member located centrally below and secured to said seat member, said partition member also being positioned between said side members and anchored thereto, a portion of each of 30 said side members being arranged to protrude beyond the inner forward edge of said seat member, and having portions cut out therefrom whereby to embracingly engage a sill of a window, 35 guide means secured to the lower face of said seat member, a horizontal hook bar slidably adjustable in said guide means and provided with a series of apertures, and a cotter pin adapted for insertion through said seat member and 40 through one of the apertures in said hook bar whereby said hook bar is secured to said seat member.

FRANK A. G. DENST.
